UNITED STATES PATENT OFFICE.

FREDERICK CHANNON PERREM, OF LEEDS, ENGLAND, ASSIGNOR TO PERREM IGNITION & ELECTRIC COMPANY LIMITED, OF LEEDS, ENGLAND, A COMPANY OF GREAT BRITAIN.

ELECTRIC IGNITION APPARATUS FOR INTERNAL-COMBUSTION ENGINES.

Application filed February 10, 1927, Serial No. 167,244, and in Great Britain May 11, 1926.

This invention relates to electric ignition apparatus for internal combustion engines, of the kind comprising the combination in a single unit of an induction coil, an electro-magnetically operated trembler, a condenser, a high tension distributor, low tension timer contacts and suitable driving gear, and the object of the invention is a unit device of compact construction which is readily accessible and which permits the working parts to be examined. In particular the trembler, high tension distributor and low tension timer can be observed in action under working conditions.

15 Ignition units of this general type are known, but in no case is it possible to examine the working parts in operation, it being necessary, for example, to remove some vital part such as the condenser, or to remove the 20 housing which renders the timer and contact breaker inoperative.

According to my present invention, the electric ignition apparatus for internal combustion engines comprises an electro-magnetically operated trembler system associated with an induction coil, low tension timer contacts, high tension distributor, condenser and driving mechanism, the whole of which is assembled as a single unit on a single base, the unit being housed in a housing of the known kind capable of being made readily removable in any suitable and known manner for ready access to the low tension timer and high tension distributor mechanism in working condition; and in this construction and arrangement the distributor shaft with its low tension timer and high tension distributor are disposed in an accessible position on a level above the induction coil, condenser and driving mechanism so as to be fully visible and readily accessible when the machine is in operation and the housing or cover is removed. Furthermore, my electric ignition apparatus is the first of its kind which embodies an electro-magnetically operated trembler system the whole of which is assembled and contained in one housing; and my low tension timer prevents destructive sparking at the point where the carbon brushes make electrical contact with the earthed segment or segments owing to the fact that a long line of contact is established as the electrical circuit is completed.

In the apparatus of the type to which the

invention relates the brush gear of the low tension timer is usually made adjustable to enable the ignition timing to be varied, while the stationary part of the high tension distributor is provided with long enough segments to cover the range of timing variation. In coil and battery ignition apparatus there is no limit on the low tension side to the extent of timing variation, but the length of the segments on the stationary part of the high tension distributor arbitrarily limits the range. A further feature of the present invention overcomes this disadvantage and permits the apparatus to have any desired degree of timing adjustment.

According to this further feature of the invention both the stationary part of the low tension timer and the stationary part of the high tension distributor are coupled together and adjusted simultaneously to vary the ignition timing.

The construction, arrangement and operation of my electric ignition apparatus is such that the electric current flows from the positive terminal of the battery by means of a lead to one end of the primary winding, a lead being taken from the other end of the primary winding to the vibrator or trembler spring. Another lead is taken from the make-and-break contact on the vibrator to a circuit or ring connecting the brushes which are on the low tension timer, so that the current flows to the earthed segment or segments of the low tension timer, a lead being continued from the earthed segment or segments to the negative terminal of the battery and to one end of the secondary winding, a lead from the other end of the secondary winding being connected to the high tension revoluble distributor, and a circuit is established between the revoluble high tension distributor or a finger on same and the lead or leads to the sparking plugs, so that as the driving mechanism is revolved sparks occur at predetermined periods in the respective sparking plugs. As all the mechanism is incorporated as a single unit in the one self contained apparatus, this ensures greater efficiency and neatness and reduces cost of manufacture, but the battery employed may be located in any other suitable position to suit requirements.

An embodiment of the invention designed for a four cylinder four cycle engine is

shown by way of example in the accompanying drawings, in which—

Figure 1 shows the apparatus in section, and

5 Figure 2 is a plan view with the housing or cover removed and omitting the fastening means for said cover.

The revoluble low tension timer indicated by 1 is made up of insulated segments, to 10 form a continuous track for the carbon brush indicated by 2, the distributor shaft 3 revolving at half engine speed. One or two of the segments 4 are earthed by means of a lead to the distributor shaft 3 which carries 15 the known kind of brush gear 6, the brush gear being connected by the known kind of continuous ring or circuit indicated by 7. A revoluble high tension distributor comprises an insulated sleeve 9 on the shaft 3, 20 the distributor 9 being provided with a finger 10 carrying a carbon brush 23 which is adapted at predetermined periods to close the circuit between itself and one of a series 25 of segments 11 on a stationary high tension insulated distributor 12 as the finger 10 passes each segment 11. The stationary part 12 of the high tension distributor is made of insulating material and is revolubly mounted on a metal pin 31 secured to the insulating 30 end 15 of the apparatus. The segments 11 are connected by flexible conductors, here shown as metallic chains 26 to the fixed terminals 27 for the sparking plug leads.

The part 12 and ring 7 are coupled together by a pair of rods 28 parallel with the shaft 3, so that both rotate together when the timing is varied and the variation is therefore not limited in any way by the length of the segments 11. To enable the 40 adjustment to be effected by the usual control mechanism, the ring 8 is provided with an arm 29.

The high tension current is led by wire 45 to the pin 31 and passes thence through a carbon brush 32 to the distributor finger 10.

The iron core 16 of the known kind of ignition coil passes through the insulated end 15. Adjacent to the outer end of the iron core 16 there is provided the known kind 50 of iron armature indicated by 17 of the known kind of trembler or vibrator mechanism indicated by 18, the ignition coil comprising a primary winding and a secondary winding, and the usual condenser (not shown) which are constructed and arranged in the known manner.

In combination with the apparatus 14, I 60 preferably use a detachable vibrator or trembler mechanism indicated by 18 and disclosed in my U. S. Patent No. 1,554,649 in

which the trembler mechanism operates in a vacuum and thus prevents rapid deterioration of the make-and-break mechanism by oxidation, or I use the known kind of 65 vibrator or trembler mechanism.

The brush 2 of the brush gear 6 is arranged to make contact with the aforesaid timer earthed segment or segments at 4, the extra long contact lines or wide surface 70 afforded at these earthed segments and the extra long contact lines or large surface of the carbon brush 2 preventing undue and injurious sparking effects as happens in ordinary timers when the carbon brushes as in 75 magnetos makes a very small line "surface" contact on the earthed timer which produces undue wear and tear between the timer and its carbon brushes.

As a result the brushes 2 and the earthed 80 segment or segments of the timer 1 form extra large bearing surfaces with each other which prolongs the life of the apparatus as the earthed segment or segments pass the brushes.

In operation, the driven shaft 25 through the spur wheel 26 drives the spur wheel 27 at half engine speed which latter rotates the shaft 3 with the low tension timer 1 and the high tension distributor 9 so that the brush 90 23 completes the circuit between itself and the segments 11 as the earthed segment or segments at 4 pass the appropriate carbon brush 2 so that the sparks are delivered at the correct time through leads to the sparking plugs of the engine.

The manner of connecting up the apparatus is described above. Any convenient source of current such as a battery or dynamo may be used.

100 What I claim is:—

Electric ignition apparatus for internal combustion engines, comprising an electro-magnetically operated trembler system, an induction coil, a distributor shaft, low tension timer contacts thereon, a rotatable ring carrying brushes co-acting with said timer contacts, an insulated metal pin coaxial with said distributor shaft, an insulated high tension distributor member rotatable on said 110 pin, segments on said distributor member connected to the high tension terminals, a distributor finger on said shaft adapted to close a circuit between itself and said segments in turn, and a member connecting said ring and said high tension distributor member so that they rotate simultaneously during ignition timing adjustment.

115 In testimony whereof I have signed my name to this specification.

FREDERICK CHANNON PERREM.
